UNITED STATES PATENT OFFICE.

NORMAN P. HARSHBERGER, OF CHICAGO, ILLINOIS.

SHINGLE.

Application filed June 16, 1926. Serial No. 116,279.

This invention relates to shingles, and it has for one of its objects providing a method for forming shingles out of large sheets of shingle material, so as to produce individual or strip shingles which can be assembled to form long strips of associated shingles having ornamental and useful projections and recesses on one edge, the contour of the edge of the entire strip being symmetrical, and the method being such that the contour of the edge may be infinitely varied without departing from the general method employed. Furthermore, the assembled strips are so formed that they may be assembled with other strips so that the ornamental exposed edges of the adjacent strips will form pleasing and symmetrical designs on a roof, and the appearance thus formed may be infinitely varied either by variations of the contours of the edges or by variations in the overlapping of the strips. Another object of the invention is to provide a method for producing such shingles by means of which the minimum amount of waste material results.

Of the accompanying drawings, Fig. 1 is a plan view of a sheet of shingle material, indicating the method by which the shingles are formed; Fig. 2 is a plan view of an individual or strip shingle; Fig. 3 is a plan view of a plurality of the shingles assembled, and as they will appear when laid on a roof; Fig. 4 is a plan view indicating the application of the method to the production of a modified form of shingle; Fig. 5 is a plan view of a method of cutting a modified form of shingle; Fig. 6 is a plan view of a single strip shingle showing a further modification, and Fig. 7 is a plan view indicating the method of forming the shingles illustrated by Fig. 6.

The shingles illustrated in the various figures are what are ordinarily called strip shingles, as each comprises more than one section, or what appears to be more than one individual shingle. In the application of my invention it is immaterial whether the shingles are strip shingles or individual shingles or, if strip shingles, how many sections there may be. Hence herein reference to individual or strip shingles refers to the shingles as illustrated in contra-distinction from the entire strips of shingles when assembled.

It will be seen by Fig. 3 that the individ-

ual shingles 10 are assembled in strips which are laid horizontally on the roof and which overlap the underlying strips of shingles. Each of these strips 11 is physically independent of the others, as the overlying strips 60 may be made to lap on the underlying strips as much as may be desired. Varying the amount of lap, however, will vary the appearance of the design, and in this case the lapping is made so as to form a symmetrical 65 geometrical figure which is substantially octagonal. In forming the strips 11 it will be seen that the adjacent ends of the shingles lap on each other so as to prevent leakage between the adjacent ends, and also that the 70 formation of the ends of the shingles is such that this lapping is accomplished without distorting in any way the general design. Also the exposed edges of the ends of the shingle are symmetrical with reference to 75 the figures themselves, as in each case the exposed edge is midway between two octagonal designs, and is at right angles to the axis of the strip of shingles.

To produce these various results, it is 80 desirable to provide a method for forming the shingles properly and with the minimum amount of waste material. The method which I provide consists in severing the sheet of shingle material, from which the 85 shingles are to be formed, longitudinally from one end to the other along lines which conform to the design desired. Inasmuch as the exposed edges of all of the shingles have similar contours, the desired result is produced by having the contours of the projections on the edges of the shingles homologous but complementary with the contours of the recesses therein. That is, the edges of the projections 12 are similar to the recesses 95 13 in each case.

But, in the formation of the shingles it is necessary to provide material for lapping the ends, and hence a portion 14 is provided on the end of each shingle which is to underlie the adjacent end of another shingle in the same strip; and, to provide this lapping portion without distorting the symmetry of the edges, my method is to cut out a waste piece 15, which separates the edges 100 16 and 17 of two adjacent shingles which are being formed a distance equal to the width of the lapping portion 14, but without in any other way varying the symmetry of the line along which the sheet is being 105 110

severed. This waste piece is formed for each of the shingles and it is immaterial how many projections 12 or how many sections the shingle may contain, there will be but one waste piece. In order to form the shingles from the longitudinal strips which are being severed from the sheet, transverse cuts 18 are made; and in order to have the lapsing edge of the shingles symmetrical with the figures, as indicated, these transverse cuts are in the central portions of the projections adjacent the waste piece and extend out to the nearest edge of the severed strip.

Although I have indicated in Fig. 1 a narrow sheet from which two strips of shingles are being formed, yet it will be understood that the sheet may be sufficiently wide to form four or more of these strips of shingles.

20 A consideration of the drawings will show that the shape of the projections and recesses may be varied as much as may be desired without departing from the method of forming the shingles set forth. This is indicated by the rectangular shaped projections and recesses of Fig. 4, in which the corners 20 are right angles and the outer edges 21 of the projections are straight and similar in length to the bottoms 22 of the recesses, 25 which are also straight. In this case the waste piece 23 is in the form of a rectangular parallelogram.

Fig. 5 shows a further modification in which the ends 25 of the projections are semi-circular and the bottoms 26 of the recesses are similar in size and shape. In this case the waste piece 27 has opposite edges corresponding in contour to the edges of the shingles from the center of a projection to the center of a recess, and it will be seen that this is true with each of the other modified forms. In the claims herein I have referred to the line along which the horizontal cuts are made as being a wave line with 35 crests and valleys which have similar contours. This is more graphically shown by the lines of Fig. 5 as these lines are all curved, but the intention is to include by the expression broken lines as well as curved 40 lines, such as are indicated in the other figures.

Fig. 6 shows a further modified form of shingle in which recesses 30 are formed, and locking tongues 31 corresponding in 45 shape to the recesses are formed on the opposite end of the shingles. By means of these tongues the exposed edge of one shingle may be locked under the adjacent end of an underlying shingle as indicated by dotted 50 lines 32. Otherwise these shingles are substantially the same as those indicated by Fig. 2; and Fig. 7 shows the method of cutting these shingles from a sheet, which corresponds to the method of cutting the other 55 shingles; and in shape the shingles, except

for the recesses 30 and the tongues 31, are similar to those of Fig. 2. The recesses 30 definitely determine the amount of lap, so that the laying of the shingles is expedited thereby.

76 Guide means, such as the notches 34 may be formed so as to assist in laying the shingles. In forming the strips of shingles the edge of the overlapping shingle is registered with the notch, as indicated by the 75 dotted line 35.

I claim as my invention:

1. A method of forming shingles from a strip of shingle material, consisting in severing the strip longitudinally along a wave 80 line having homologous crests and valleys, until a predetermined point of separation is reached, and, from this point consisting in severing the strip along two separated complementary lines meeting at another point, 85 then, from the point of meeting, consisting in severing the strip longitudinally along a line similar to the said wave line, until another point of separation is reached, and in continuing said severing in a similar manner so long as may be desired, thus forming 90 independent severed strips, at the same time the method includes the severing of said severed strips along transverse lines extending from certain equally spaced crests and 95 valleys to the respective nearest edge of said shingle material strip.

2. A method of forming shingles as set forth in claim 1 in which said complementary lines form symmetrical continuations 100 of the respective wave lines preceding and following said points of separation and meeting.

3. A method of forming shingles according to claim 1 in which the severing is along 105 as many transverse lines as there are points of separation and meeting and the said lines are equal distances from the respective points.

4. A method of forming shingles according to claim 1 in which said transverse lines are at right angles to the edges of the strip of material.

5. A method of forming shingles according to claim 1 in which said transverse lines 115 extend from the central portions of the crests and valleys.

6. A method of cutting shingles according to claim 1 in which said crests and valleys have straight flat tops and bottoms. 120

7. A method of cutting shingles according to claim 1 in which said crests and valleys have straight flat tops and bottoms and in which the wave lines comprise straight lines running from the ends of the valleys 125 to the ends of the adjacent crests.

8. A method of cutting shingles according to claim 1 in which said crests and valleys have straight flat tops and bottoms and in which the wave lines comprise straight 130

lines running obliquely from the ends of the flat valleys to the respective adjacent ends of the flat crests.

9. A method of cutting shingles according to claim 1 in which said crests and valleys have straight flat tops and bottoms, and in which the wave lines comprise straight lines running obliquely from the ends of the flat valleys to the respective adjacent ends of the flat crests, and in which the said straight lines form obtuse angles with the flat crest and valley lines with which said straight lines are associated.

10. A method of cutting shingles from a strip of shingle material which consists in severing the strip longitudinally along a line having bends therein, so as to form similar and equal projections and recesses on the two severed edges, until a certain point is reached, and from this point in severing the strip along two bent lines meeting at another point, thus severing from the strip a waste piece, and in then from the point of meeting severing the strip longitudinally along another line similar to the first mentioned line, and in severing the strip transversely across some of the narrow portions of the severed strips.

11. A method of cutting shingles accord-

ing to claim 10 in which the strips of shingle material are cut so that the said waste pieces have homologous opposite edges which are homologous with certain portions of said bent lines.

12. A method for forming shingles according to claim 1 in which the distance between said complementary lines is made equal to the distance it is desired to have the adjacent shingles lap on the roof.

13. A method of forming shingles from a strip of shingle material, consisting in severing the strip longitudinally along a wave line until a predetermined point of separation is reached, and, from this point consisting in severing the strip along two separated complementary lines meeting at another point, then, from the point of meeting, consisting in severing the strip longitudinally along a line similar to the said wave line, until another point of separation is reached, and in continuing said severing in a similar manner so long as may be desired, at the same time the method includes the severing of said severed strips along equally spaced transverse lines.

In testimony whereof, I hereunto set my hand.

NORMAN P. HARSHBERGER.
